(57) **CLAIM**

The ornamental design for a cat litter box, as shown and described.

DESCRIPTION

FIG. 1 is a perspective view of a cat litter box, showing our new design;

FIG. 2 is a perspective view with the lid open thereof;

FIG. 3 is a perspective view of FIG. 1 rotated by 180 degrees thereof;

FIG. 4 is another perspective view thereof;

FIG. 5 is a perspective view in the using state thereof;

FIG. 6 is a front view thereof;

FIG. 7 is a rear view thereof;

FIG. 8 is a left side view thereof;

FIG. 9 is a right side view thereof;

FIG. 10 is a top plan view thereof; and,

FIG. 11 is a bottom plan view thereof.

The broken lines depict portions of the cat litter box, and form no part of the claimed design.

1 Claim, 11 Drawing Sheets
